UNITED STATES PATENT OFFICE.

MATHIAS FRANK McNELLY, OF CHICAGO, ILLINOIS.

ACETYLENE-GAS GENERATOR.

No. 836,272.

Specification of Letters Patent.

Patented Nov. 20, 1906.

Application filed November 22, 1905. Serial No. 288,615.

To all whom it may concern.

Be it known that I, MATHIAS FRANK McNELLY, a citizen of the United States, residing at Chicago, in the county of Cook and State of Illinois, have invented a new and useful Improvement in Acetylene-Generators, of which the following is a specification, reference being had to the accompanying drawings, forming part thereof.

The object of my invention is to provide a new and improved feeding device for an acetylene-gas machine.

In the drawings, Figure 1 shows a side elevation of a portion of machine with the neck thereof shown in vertical section, the internal mechanism being shown in section and the actuating-rod and its mechanism being shown in longitudinal section; Fig. 2, a plan view of the feeding cup or bucket; Fig. 3, a cross-sectional view of the neck, taken on line *a a* of Fig. 1; Fig. 4, a top or plan view of the shelf or bracket on which the cup rests, and Fig. 5 a side elevation of the bucket or cup.

The numeral 1 shows the neck of the machine, and 2 a funnel-shaped member arranged to receive the calcium carbid from the upper chamber and direct it into the cup or bucket 5, the numeral 3 showing a system of wires bent over the funnel-shaped member to prevent the whole weight of the carbid from pressing into the funnel-shaped member and packing the carbid therein.

4 represents the operating-rod passing through a stuffing-box and carrying the actuating-rod 4', which slides the cup 5 back and forth across the shelf or bracket 5' when the rod 4 is revolved. The stuffing-box is seen at 4⁵, and at 4³ is seen a rod to loosen the carbid in the extreme neck of the member 2 provided it becomes packed at that point. The outer end of rod 4 carries the crank 4⁷ and passes loosely into crank 4⁶, the lower end of said last-named crank entering socket 4⁹ and is clamped therein, when desired, by the spring-plunger 4^a, set in the casing 4⁸. The rod 4⁶ enters and is fastened tightly in crank 4⁶ and on its outer end carries a collar, which in turn carries arm 4¹⁰, the end of the arm passing through an opening in the trough-like member 9', which is attached to and rises and falls with the gasometer 9 setting in the water-tank 10. The cup 5 is centrally divided by the partition 6 and has the lug 7 passing underneath the shelf 5' to prevent any separation of the cup 5 from shelf

5' during operation. The shelf 5' has two openings through it, 5², (see Fig. 4,) and they are arranged so that as the cup is slid over to one side or the other as far as it will go the partition 6 in cup 5 will lie directly along the slanting edge of the hole it is moved toward. As cup 5 has no bottom, one half of its open bottom edge will rest over one of the openings 5², and the contents of that half of the cup 5 will fall into the generator and be converted into gas, while the other half will not be discharged until the cup is moved the other side of the shelf. In the bottom edge of the cup 5 is a small notch or opening 5³, so as to allow any pieces of carbide that may get in the way to pass into this opening and ease the cup, so it will slide easily. The cup is pivoted at 8 to the shelf, so it can be swung from side to side.

The operation is as follows: As the gas is formed in the gasometer the bell or part 9 rises and carries the trough-like member 9' up with it. As it rises the arm 4¹⁰ is also carried upward, and this rotates rods 4⁶ and 4⁷ and cranks 4⁶ and 4⁷, and actuating-rod 4' moves like a pendulum sidewise, making half of a pendulum's stroke and carrying the cup 5 across the shelf until one-half its open bottom rests over one of the openings 5², when one-half its charge of carbide will fall into the generator. As the gas is used commercially in lighting or for other purposes, it leaves the gasometer and it falls and carries the actuating-rod 4' in the opposite direction and carries the cup with it until one-half its open bottom is over the opposite opening 5², when its load is discharged and produces more gas to take the place of that that is being used. The cranks 4⁶ and 4⁷ are used as follows: If it is desired to give the carbide in hopper 2 a start or to assist it in feeding, spring-plunger 4^a is drawn and crank 4⁷ is used as a crank by moving it up and down, moving stirrer 4⁶, which causes the hopper 2 to feed freely. When the crank 4⁷ is thus operated, crank 4⁶ is not disturbed, as the rod 4 rotates freely in its opening in crank 4⁶. Lever 4⁶ is used separately from lever 4⁷ by freeing spring-plunger 4^a and using 4⁶ in making any adjustments necessary with the trough-like member 9' that may be desired, thus using crank 4⁶ as a crank, for which it was intended.

Having now described my invention, so that those skilled in the art may know how

to make and use the same, what I desire to secure by Letters Patent is—

1. In a gas-machine a feeder for the generator consisting of a shelf or bracket having unobstructed openings through it a bottomless cup or bucket arranged to be slid back and forth over the shelf or bracket, said cup having a partition dividing it into a plurality of compartments, the bottomless compartments being arranged to register with said openings in the shelf at predetermined times; means for sliding the cup back and forth over the shelf; all so arranged and operating that when the cup is slid across the shelf or floor one at least of its compartments will register with an unobstructed opening in the shelf and discharge its load into the generator while the other compartments will rest on the imperforate portion of the shelf and not dump its load until the bucket is moved oppositely over the shelf substantially as described.
2. In an acetylene-gas machine a feeder for the generator consisting of a bracket or floor having predetermined unobstructed openings through it; a moving bottomless bucket having a partition dividing it into a plurality of pockets and means for moving said bucket back and forth across said floor so as to present each pocket in predeter-

mined order over an opening in said floor; and having means for supplying said bucket with carbid at prearranged times substantially as described.

3. A feeder-operator for a gas-machine consisting of a compound revoluble rod one end of which enters the feeder in proximity to the point of exit of the carbid; a lever carried by the rod and in connection with a movable bracket; a crank attached to the rod whereby it may be rotated having a recess and a spring-plunger operating in said recess; a second crank carried loosely on one portion of said compound rod and also tightly affixed to the other portion of said rod and operatively connected with the bell of the gasometer and arranged so that as the bell rises or falls the compound rod will be rotated and the bucket moved and so arranged that either portion of the rod may be revolved independently of the other portion or be revolved as one continuous rod substantially as described.

In testimony whereof I have signed my name to this specification in the presence of two subscribing witnesses.

MATHIAS FRANK McNELLY.
